UNITED STATES PATENT OFFICE.

HARRY F. SMITH, OF LEXINGTON, OHIO, ASSIGNOR TO THE SMITH GAS ENGINEERING COMPANY, A CORPORATION OF OHIO.

ROTARY PUMP.

1,310,584.

Specification of Letters Patent. Patented July 22, 1919.

Application filed August 25, 1917. Serial No. 188,238.

To all whom it may concern:

Be it known that I, HARRY F. SMITH, a citizen of the United States of America, residing at Lexington, Richland county, Ohio, have invented certain new and useful Improvements in Rotary Pumps, of which the following is a full, clear, and exact description.

This invention relates to a form of rotary pump, and more particularly to a rotary pump in which use is made of a liquid abutment which maintains its effective form under the action of centrifugal force.

In many pumps heretofore used there is metal to metal contact between the working parts, tending to greatly lessen efficiency. Especially is this true where the fluid being pumped is of a viscous nature or is of such character that it hardens if left standing. In such cases some of this fluid invariably works in between the contacting metal parts, and causes binding or sticking thereof. This tendency is very marked where gas containing tarry matter, such as producer gas which contains large quantities of tar fog suspended therein, is being pumped. With the prevalent types of pumps it is found that this tar fog collects between the working parts, and after cooling, binds them so tightly that the parts must be steamed in order to soften the tar sufficiently for operation to be resumed. In my invention I avoid this difficulty entirely by completely eliminating all metal to metal contact of the working parts of the pump, and by dispensing with all valves. By this arrangement I avoid all metal to metal friction between the working parts of the pump, and am thus enabled to attain a higher speed which permits of a decrease in size of the various parts without any loss in the quantity of work done.

A type of pump embodying my invention is shown in the accompanying drawing, in which:

Figure 1 is a view at right angles to the axis of the rotor with parts removed to show the interior of the cylindrical casing;

Fig. 2 is a view of the device at right angles to Fig. 1 with parts thereof broken away to more clearly disclose the structure;

Fig. 3 is a sectional view through the rotor along the line 3—3 of Fig. 4;

Fig. 4 is a sectional view along the line 4—4 of Fig. 3;

55

Fig. 5 is an elevation of the rotor;

Fig. 6 is an elevation of a modified form of rotor;

Fig. 7 is a sectional view through the modified form of rotor along the line 7—7 of Fig. 8;

Fig. 8 is a sectional view along the line 8—8 of Fig. 7.

In the drawing in which like characters of reference designate like parts throughout the various views, 1 is a cylindrical casing having an inlet 2 and an outlet 3. Both the inlet and the outlet open directly into the casing 1 without any controlling valves whatsoever, the flow of fluid into and from said casing being unregulated except by the speed of the pump rotor.

Mounted in the pump casing is a rotor element 4 carried by a shaft 5, which shaft is supported by suitable bearings, one of which is illustrated conventionally at 6. This shaft is so mounted that the axis thereof is out of line with the axis of the cylindrical casing 1, the rotor itself being cylindrical in general outline so that its rotation will be eccentric to the said casing. The rotor 4 consists of a hub portion 7, having circular flanges 8 upon each end thereof. Extending between the flanges 8 and connected to the hub portion 7, is a fin or piston 9, the free end of which is flush with the periphery of the flanges. This fin 9 is in reality a piston, since in operation it is the element which impels the gas through the casing, the gas being under greater pressure on one side than the other. Extending through the rotor is an axial passage 10 adapted to receive the shaft 5. Extending part way through the hub is a longitudinal inlet passage 11, its free end opening through one end of the rotor, as shown clearly in Fig. 5. This inlet passage has its free open end at all times connected to that end of the casing into which the inlet 2 opens, so that it is always in free communication with such inlet. In the wall of hub 7, adjacent the base of piston 9, is a slot 12 connecting the space between the flanges 8 with the inlet passage 11. Extending part way through the hub 7 is a second passage 13, having the free end thereof opening through that end of the

100

105

110

rotor element opposite to the end through which the passage 11 opens. This passage has its free open end at all times connected to that end of the casing from which the outlet 5 let 3 leads, so that it is always in communication with such outlet. Attention is called to the fact that so long as rotation of the rotor is in one direction, the outlet passage 11 always serves as the inlet, while the passage 10 13 always serves as the outlet. It is thus seen that valves controlling these passages are unnecessary, and that metal to metal contact of the rotor and casing, may be entirely dispensed with. This passage 13 15 which I will hereinafter call the outlet passage, has a slot 14 adjacent the base of piston 9, and upon the opposite side thereof from the slot 12, which connects the passage 13 with the space between the flanges 8 in a manner similar to that described above and 20 clearly illustrated in Fig. 5. The rotor 4, as shown in the drawings, is so mounted in the casing that no part of it approaches contact with any part of the casing. That is, all 25 metal to metal contact between the rotor and the casing is avoided. This is very advantageous; for, as stated above, all binding or sticking of the working parts of the pump is thus entirely avoided. Also, contacting 30 metal parts will very quickly wear, and allow leakage therebetween, which, of course, decreases efficiency, and at the same time increases the tendency to bind or stick. Such 35 can not take place in my device.

35 In the casing 1 is a quantity of liquid 15. The rotor 4 is so mounted in the casing 1 that the hub 7, the flanges 8, and the piston 9 thereof, are always partly immersed in the liquid 15 when the pump is in operation.

40 Rotation of the rotor 4 will bring about a consequent rotation of the liquid 15. This rotation of the liquid 15 gives rise to a centrifugal force which will cause it to assume the shape of a cylinder, as clearly shown in 45 Figs. 1 and 2, which cylinder is concentric with the casing 1, and consequently eccentric to the rotor 4. The liquid 15 thus assumes the form of a smooth cylinder capable of readily yielding to allow the piston to pass 50 in and out thereof, and to compensate for irregularities in the casing and rotor, but sufficiently rigid to act as an abutment against which the gas is compressed for forcing it through the pump. It can be 55 clearly seen that at the lower part of the cylinder, the flanges 8 and piston 9 will dip more deeply into the liquid than at the upper part thereof. The quantity of liquid constituting this cylinder is so proportioned that 60 when in lowest position, the piston 9 is completely immersed, while in uppermost position, only the free edges of the flanges 8 and piston 9 are submerged. Leading into the casing is an outlet pipe 16 for supplying the 65 fluid 15 thereto, while leading from the cas-

ing is a pipe 17, having a trap 18 therein for drawing off any surplus fluid introduced through 16. In this way the quantity of fluid 15 is kept constant.

Assuming that the direction of rotation 70 of the rotor 4 is clock-wise, it is evident that upon upward movement of the piston 9, the space between hub 7, the inner wall of the liquid ring 15, the flanges 8, and the lower side of the piston 9, will be continuously increasing, while the corresponding space upon the upward side of the piston 9 will be decreasing. Upon upward movement, therefore, there will be a tendency for a vacuum to form below the piston 9. At such time 75 the slot 12 is connected with this increasing space, thereby connecting it through the passage 11 with the inlet 2. Any tendency toward the forming of a vacuum in this increased space will, therefore, result in an 80 inflow of gas from the inlet 2 through the passage 11 and slot 12. Likewise such rotation of the rotor, which, as stated above, results in a continuous decreasing of the space existent above the piston 9, will necessarily result in forcing out through the slot 85 14 and passage way 13 into the outlet 3 any gas contained in such continuously decreasing space. Since the gas contained in the decreasing space is the same gas as drawn 90 into the increasing space on the preceding revolution of the rotor, rotation of the rotor will result in a drawing in of gas from the inlet pipe 2, and an ensuing forcing out of 95 that same gas into the outlet pipe 3. It is evident from the above, that the quantity of 100 gas pumped by my apparatus is entirely dependent, for a given size of pump, upon the speed of rotation of the element 4. And as set forth above I am able to attain easily 105 and safely, a very high speed of rotation, because of metal to metal contact of the working parts, along with friction resulting from such contact, being eliminated. It is thus seen that the liquid cylinder 15 acts as 110 an abutment which co-operates with the rotor-piston to force gas through the passages 11 and 13. As stated above hub 7 of the rotor is always partly submerged as are also the flanges 8 and piston 9. Rotation of the 115 rotor merely causes a greater or less submerging of the flanges and piston with a consequent increase or decrease in the space inclosed therebetween.

In Figs. 6—7—8 I have shown a modified 120 form of rotor, in which I have three flanges 19 similar to the flange 8, and two pistons 20—21 similar to the piston 9, these pistons being located upon diametrically opposite sides of the rotor element. In place of two 125 passages 11 and 13, there are four passages 22—23—24—25. Two of these passages 22—23 open adjacent the piston 20; the other two 24—25 open adjacent the piston 21. This form of rotor may be substituted 130

for the single-phase rotor shown in Fig. 2. The mode of operation is the same as that of the rotor described above, the only difference being that with a rotor such as shown in Fig. 6, a more continuous flow of liquid from the pump is secured, inasmuch as two pulsations will be secured to each complete revolution of the rotor element in place of one pulsation secured upon a complete revolution of the rotor element shown in Fig. 2. In actual practice I have found a multi-phase rotor element, such as shown in Fig. 6, preferable to the single-phase element shown in Fig. 2. The mode of operation with the multi-phase element is sufficiently clear in view of the method of operation described above to make unnecessary any further description thereof.

From the above description it is quite obvious that I have invented an apparatus which is very simple in structure and mode of operation, an apparatus which is more effective for the purposes for which designed than any pump heretofore known, and one that is practically "fool proof". While I have shown what I consider at present, the best adaptation of my invention, I by no means limit myself to the disclosure of my invention set forth above, inasmuch as there may be numerous changes in mechanical details of construction without in any way changing the scope of my invention. And for a true definition of the scope of my invention, reference should be had to the appended claims.

What I claim as new and desire to secure by Letters Patent is:

1. In a pump, the combination of a casing having valveless inlet and outlet ports therein, said casing being adapted to contain a quantity of liquid which during operation of the pump is caused to assume the form of a revolving liquid cylinder; a rotor in said casing and free from contact therewith; and passages in said rotor connecting the inlet and outlet ports; said rotor during operation of the pump coöperating with the revolving liquid cylinder to force fluid through the passages.
2. A pump comprising a cylindrical casing, adapted to contain a quantity of liquid which during operation of the pump is caused to assume the form of a revolving liquid cylinder; inlet and outlet ports in the casing at all times freely connected to the interior thereof; a rotor in said casing and entirely free from contact therewith; and passages in said rotor connected respectively to the inlet and outlet ends of the casing; said rotor during operation of the pump coöperating with the liquid cylinder to force fluid through the rotor passages from the inlet to the outlet end of the casing.
3. In a pump, the combination of a cylindrical casing having inlet and outlet ports at

all times freely connected to the interior thereof, said ports being connected respectively to opposite ends of said casing, the casing being adapted to contain a quantity of liquid which during operation of the pump is caused to assume the form of a revolving liquid cylinder; an eccentric rotor in the casing having its opposite ends respectively adjacent the said inlet and outlet ports; and passages in the rotor opening through the opposite ends thereof; the liquid cylinder during operation of the pump being concentric with said casing and adapted to coöperate with the rotor to cause flow of fluid through the passages in said rotor from the inlet to the outlet end of the casing.

4. A pump comprising a casing having inlet and outlet ports leading thereto, said casing being adapted to contain a quantity of liquid which during operation of the pump is caused to assume the form of a revolving liquid cylinder; a rotor in said casing free from contact therewith, a peripheral groove extending part way around said rotor, a passage in the rotor connected at all times to the inlet end of the casing, and a second passage in the rotor connected at all times to the outlet end of the casing, said passages being at no time connected to each other during operation of the pump but each connected to said peripheral groove; the rotor upon operation of the pump coöperating with the liquid cylinder to force fluid from the inlet end of the casing through the first passage, the peripheral groove, and the second passage into the outlet end of the casing.

5. A pump comprising a cylindrical casing having its ends freely connected respectively to inlet and outlet passages, said casing being adapted to contain a quantity of liquid which during operation of the pump is caused to assume the form of a revolving liquid cylinder; a rotor mounted eccentrically within the casing and entirely out of contact therewith; flanges at the opposite ends of the rotor, said flanges during operation of the rotor being at all times immersed in the liquid cylinder to form a closed chamber; a passage in the rotor connected at all times to the inlet, a second passage in the rotor connected at all times to the outlet, said passages being connected to the said closed chamber but not to each other; and means on the rotor coöperating, during rotation of the rotor, with the liquid cylinder for causing fluid to pass through the passages and closed chamber from the inlet to the outlet passage of the casing.

6. A pump comprising a cylindrical casing, said casing being adapted to contain a quantity of liquid; an inlet port at all times freely connected to the interior of the casing at one end thereof, and an outlet port at all times freely connected to the interior of the

casing at the other end thereof; a rotor in said casing eccentric thereto and entirely free from contact therewith, flanges on the ends of said rotor, inlet and outlet passages in said rotor extending part way therethrough and at all times connected respectively to the inlet and the outlet ends of the casing, a fin on the rotor between the flanges, slots in said rotor adjacent the fin and upon opposite sides thereof, said slots leading into the inlet and outlet passages of the rotor respectively; the liquid within the casing being caused during operation of the pump to form a rotating liquid cylinder concentric with the casing and eccentric to the rotor, said liquid cylinder during operation of the pump at all times covering some part of the rotor flanges and fin and cooperating therewith to cause the space between the flanges and fin to alternately increase and decrease to force fluid from the inlet end of the casing through the rotor to the outlet end thereof.

7. A pump of the character described, comprising a casing, inlet and outlet ports at all times in free communication with the interior of the casing; a rotor in said casing, passages in said rotor adapted for free communication, one with the inlet port only and the other with the outlet port only, and a vane or fin carried by said rotor and

adapted to at all times separate the inlet and outlet ports from communication with each other.

8. A pump of the character described, comprising a casing, inlet and outlet ports at all times in free communication with the interior of the casing; a rotor in said casing, passages in said rotor adapted to communicate one with the inlet ports and the other with the outlet port of the casing, and a vane or fin carried by said rotor and adapted to at all times separate the inlet and outlet ports from direct communication with each other.

9. A pump of the character described, comprising a casing, inlet and outlet ports at all times in free communication with opposite ends of the interior of the casing; a rotor in said casing and free from contact therewith, a passage in said rotor and adapted to at all times freely communicate with the inlet end of the casing; a second passage through said rotor adapted to at all times freely communicate with the outlet end of the casing, and a vane or fin carried by said rotor and adapted to at all times separate the two said passages from communication with each other.

In testimony whereof I affix my signature.

HARRY F. SMITH.
